TIMING DEVICE

Gerald C. Syrek, Vancouver, Wash.

Application October 24, 1938, Serial No. 236,709

5 Claims.

(Cl. 200—28)

This invention relates to timing devices and is particularly adapted to be used in connection with the posting of time units, through the use of lamp banks, such as commonly used on race tracks and the like.

The primary object of the invention is to provide a timer that will make and break contacts almost instantaneously.

Another object of the invention is to make and break a multiple of contacts practically simultaneously.

A further object of the invention is to provide a timing device that will post information through lamp banks and so forth, at a number of different locations in synchronism.

A still further object of the invention is to provide a design of contact brush and contacts that can be adjusted accurately, and maintained in accurate adjustment.

Another object of the invention is to provide a contact brush that will close a multiple of contacts, but at the same time this brush only contacts one contact point directly, eliminating any chance of lag between each closure of contacts.

An still a further object of the invention is the snap action of opening and closing contacts through the use of spring tension between contacts.

These and other incidental objects will be apparent in the drawings, specification and claims to follow.

Figure 1 is an end elevation of the timing unit, looking towards the driven end showing the brush contact arm.

Figure 2 is a side elevation of Figure 1.

Figure 3 is an enlarged fragmentary sectional view, taken on line 3—3 of Figure 1, looking in the direction indicated.

Figure 4 is a fragmentary sectional view of Figure 3, looking in the direction indicated, parts broken away for convenience of illustration.

Figure 5 is a front elevation of the timer, partially broken away for the convenience of illustrating the manner, also process of contacting is illustrated.

Figure 6 is a diagrammatical electrical wiring layout of the timer, in relation to the operating relay for controlling the posting of time units, which in this case is being done by quick acting lamps.

My new and improved timer consists of a main body 1 mounted upon a base 2, this body is preferably made of electrical insulating material, although I do not wish to be limited to this type of construction.

The purpose of this main body is to provide a structure for carrying all stationary contacts. A revolving brush arm 3 is mounted upon the shaft 4 and is revolved at a predetermined speed by a source of power not here shown. A flat spring brush 5 is mounted at the outer end of the arm 3 and may be adjustable, for instance, by the adjusting screw 6, which accurately positions the brush 5 relative to its distance away from the shaft 4.

An annular groove 7 surrounds the body 1 and is for the purpose of accommodating the operation of contacts. Contacts 8 are mounted within one of the side walls 9 of the groove and extend into the groove, best shown in Figure 3. A row of contacts 10 are mounted directly opposite on the other side wall 11 of the groove 7. A more complete description of these contacts will follow later.

20 Spring contact bars 12 are mounted in the body portion 1, having their outer ends working freely within the groove 7 and the opposite end, which is anchored in the body portion, terminating in electrical terminals 13.

23 Referring to Figures 4 and 5, the spring contact bars 12 assume a normal position just ahead of but not in contact with the contact terminals 8 and 10. In operation the shaft 4 rotates carrying arm 3 and the brush 5 against the outer ends 20 of the contact bars 12, forcing the bar 12 against the contacts 8 and 10. The brush bar 5, as shown best in Figure 4, flexes, as shown, also flexing the contact bar 12 until it reaches a point where it slips off the end of the bar 12 striking the next bar 12A. Herein is one of the secrets of quick breaking and making of contacts. When the brush 5 slips off the end of the bar 12 the flex within the bar 12 immediately breaks contact while the momentum developed within the brush 40 bar 5 strikes the bar 12A a blow sufficient to carry it against contacts 8A and 10A, this completes an electrical circuit through the brush 5, contact bar 12A which in turn supply the contacts 8A and 10A with electric energy which is delivered to their respective relays hereinafter described.

Referring now to Figure 6, the lamp banks 13, 14 and 15 are shown herein to read twenty-eight and one-fifth seconds, these lamps are controlled by relay switches 16, 17 and 18. While only three relays are shown the different lamp banks require more than one relay to control the stencilling out of the required numerals which will be more fully described later.

55 Electrical energy is supplied through the con-

ductor 19 and through the brush 5 to the contact bar 12, conductor 20 to the main conductor 21, lead 22 to the solenoid of the relay 23 thence to the line 24, completing the relay operating circuit, this causes the relay switch 16 to close an electric current into the contacts 25 and leads 26 leading to a lamp bank 15, completing the circuit through the proper lamps to give the reading controlled by the relay 23, this circuit is closed through the conductor 27, contact 28, through switch bar 16 into the contacts 25 and leads 26 to the proper lamps in lamp bank 15, thence to the main line supply 29.

Almost simultaneously with the contact of brush 5 with the bar 12 closing the above circuit, just described, the bar 12 strikes the contacts 8 and 10. We will not follow out the current through the contact 10. Current flows through the conductor 30, conductor 31, relay solenoid 32 into common conductor 24, completing relay circuit. The solenoid 32 closes the switch bar 17 with the contacts 33 and contact 34, which will complete an electric current from the conductor 27, contact 34, contact bar 17, contacts 33 and following the dotted indicating line 35 to the lamp bank 14 stenciling out the proper reading for that particular relay. It will be noted that there are a multiple of contacts 10 joined together, the reason for this is to retain the reading on the lamp bank 14 until the proper number of units are stenciled on the preceding bank which is adding up the proper units to equal the next denomination, which we have just described in the operation of relay 32.

Referring back again to the contacts 8, it will be noted that there are a great number of these contacts connected together through the conductor 38, for the proper posting just described, which in this case represents ten complete groups of units of the contacts 10, which are indicated by numbers 36.

We will now follow an electric circuit from the contacts 8 to their respective relay, current flows from the brush 5 to the bar 12, contact 8, conductor 37 to solenoid 38, energizing the solenoid 38, this closes the contact bar 18 with the contacts 39 and supply contact 40, completing an electric circuit through the dotted indicating line 41 to the lamp bank 13, completing the reading of the lamp units in this hook-up. The leads 42 lead to the relays, not here shown, for operating the lamps within the bank 15, which would be four in number in this case, in order to take care of the other units. Conductors or leads 43 lead to the additional relays controlling the lamp bank 14, not here shown. The conductors 44 lead to other relays, not here shown, for controlling a further reading on the lamp bank 13.

I do not wish to be limited to the particular hook-up of my timer with the mechanisms and relays to be operated, including the posting system shown, because my timer is adapted to be

used in connection with many variations of mechanisms to be operated by a multiple switch mechanism of the type shown, described and claimed relating to my timer.

5. What is claimed to be new is:

1. A timer system control including a fixed body having an annular channel, an arm mounted for rotation on said body and carrying a finger depending within the channel, a series of spring contact members fixed in the base of the channel and extending into the path of movement of the finger, and a series of independent contacts extending through the walls of the channel and into the path of movement of the member, the member being normally free of engagement with the contacts and movable into electrical engagement with two such contacts in the movement of the member in response to the engagement and movement of the finger.

15 2. A construction as defined in claim 1, wherein the contact member and finger are of spring type and wherein the finger bends the contact member engaged thereby toward and into engagement with the contacts, the finger riding off the member with an inherent spring tendency to snap into contact with the next successive member, whereby substantial continuity of contact is maintained.

25 3. A construction as defined in claim 1, wherein the members are flat spring strips embedded in the base of the annular channel with a lateral projection through the body for electrical connection, and wherein the contacts are in the form of points projecting through the opposite walls of the channel in the path of movement of the members and electrically connected beyond the body in the defined circuit.

30 4. A timer control comprising a fixed element, a successive series of flexible contact members mounted in the element, a flexible energizing finger movable for successive engagement with the members and serving with the members to complete a circuit from a source of power, the cooperation of the finger and contact members serving to bend the respective members during engagement and tension the energizing finger for independent inherent movement when riding beyond a particular contact member, the inherent energization of the finger when released from a particular contact member causing such finger to immediately spring into engagement with a successive contact member for contact therewith, whereby to ensure a contact relation between the finger and successive contacts at a speed exceeding that incident to the bodily movement of the finger.

45 5. A construction as defined in claim 4 wherein the fixed element includes a plurality of fixed contact points arranged in spaced pairs, with each pair in position to be engaged by a contact member under the described movement of the energizing finger.

GERALD C. SYREK.
